UNITED STATES PATENT OFFICE.

HENRY ALLEN AVERY, OF GROTON, NEW YORK, ASSIGNEE, BY MESNE ASSIGNMENTS, TO L C SMITH & CORONA TYPEWRITERS INC., OF SYRACUSE, NEW YORK, A CORPORATION OF NEW YORK.

TYPEWRITING MACHINE.

Application filed April 4, 1925. Serial No. 20,729.

This invention relates to improvements in typewriting machines, and more particularly to portable typewriting machines which are transported in carrying cases.

- 5 The invention has for its objects to provide a simple and inexpensive case-shifting and locking device for portable typewriting machines having shifting platens adapted to be collapsed without releasing the shift lock;
- 10 to provide a case-shifting and locking mechanism for a typewriting machine having a shiftable platen adapted to be collapsed by pressure from a case cover; to provide a shifting and locking mechanism for the
- 15 platen carriage of a portable typewriting machine adapted to positively shift the platen carriage and parts movable therewith to upper case position and then spring or yield to permit secure locking of the parts,
- 20 said mechanism being also arranged so that the platen carriage and parts shiftable therewith may be forced to normal position by back pressure resulting from forcing an enclosing case cover down over the machine
- 25 with the platen carriage locked in upper case position.

Other objects and advantages of the improvements will appear from the following description of the preferred embodiment of the invention illustrated in the accompanying drawings:

In the drawings:

Figure 1 is a vertical longitudinal sectional view of a typewriting machine showing the collapsible case shifting and locking mechanism, the platen carriage being shown locked in upper case position;

Fig. 2 a view similar to Fig. 1 showing the main frame standing on the base member of a closed carrying case and the platen carriage forced down to and held in lower case position by the cover member of the case with the shift lock still in locking position;

Fig. 3 a perspective view showing the case shift mechanism, the parts being in normal lower case position;

Fig. 4 a detail view showing the yielding connection between the left hand shift key lever and the shift frame, the parts being in normal or lower case position; and

Fig. 5 a detail view showing the rigid connection between the right hand shift key lever and the shift frame, the parts being in normal or lower case position.

The improvements have been illustrated 55 in connection with a portable typewriting machine known as the "Corona four" and its carrying case, but may be embodied in other machines.

The main frame 1 of the machine is provided with suitable rubber supporting feet 60. The platen 3 is journaled in the end plates of a platen carriage 4 which is supported in a downwardly and rearwardly inclined position on suitable anti-friction bearings to travel transversely of the machine on a downwardly and rearwardly inclined carriage bed 5. The carriage bed 5 is shiftable upwardly and rearwardly at right angles to the plane of the bed from the position 70 shown in Fig. 2 to the position shown in Fig. 1 to change case. An anti-friction supporting and guiding means for the bed is provided comprising a pair of brackets 6 extending downwardly and forwardly from 75 the under side of the bed adjacent opposite ends of the bed and rigidly secured at their upper ends to said bed, these brackets being connected at their lower ends by a transverse brace rod 7 and provided with raceway slots 8 for anti-friction balls 9 traveling in raceway channels 10 in a pair of brackets 11 secured to the main frame of the machine at opposite sides thereof. The channels 10 in the brackets 11 extend in a plane at right 85 angles of the plane of the carriage bed 5 parallel with the slots 8 in the brackets 6.

A rock shaft 12 extends transversely of the machine and is journaled at its ends on the main frame 1. A pair of forwardly and 90 upwardly extending rock arms 13 fixed on said shaft are provided at their forward ends with outwardly extending pins 14 engaged in upwardly and forwardly extending slots 15 in the brackets 6. The weight of the 95 shiftable carriage support and parts mounted thereon is partly counter-balanced by a coil spring 16 connected at one end to a central rock arm 17 extending forwardly from the rock shaft and at its other end to a 100

bracket 18 secured to the main frame. In the normal lower case position of the platen carriage the stop lugs 19 on brackets 6 abut against the upper end of stop screws 20 on the brackets 11. The carriage is arrested in upper case position by the engagement of stop screws 21 on brackets 6 with stop lugs 22 on brackets 11.

The carriage support is adapted to be shifted to upper case position either through the medium of a temporary shift lever 23 or through the medium of a shifting and locking lever 24, said levers being of general arch form and pivoted intermediate 15 their ends substantially at the highest points thereof on horizontal pivot screws 25 supported on the main frame adjacent the top of said frame and forward of the shiftable platen support. The downwardly and forwardly extending arm of the shift lever 23 is provided with a shift key 26 at its forward end and is formed at its rear end with a fork 27, one finger of which engages under the right hand pin 14 and the other finger 25 of which engages over said pin. The downwardly and forwardly extending arm of the shifting and locking lever 24 is provided with a shift key 28 at its forward end and is provided at its rear end with a single 30 finger 29 which engages over the left hand pin 14. A stiff coil spring 30 is connected at its upper end to lever 24 just forward of the finger 29 and extends downwardly and forwardly therefrom with its axial line parallel with the direction of motion of the shifting platen support and is connected at its lower end to a forwardly extending finger 31 formed on the lower end of the left hand bracket 6. The spring 30 is normally 35 under tension and is sufficiently strong or stiff to maintain the finger 29 in engagement with the left hand pin 14 when the platen support is in lower case position and during movement of said support to upper 40 case position. In other words, said spring is made of such strength that whenever the key 28 or key 36 is depressed in operation of the machine the shiftable carriage support and the parts thereon will be moved 45 from lower case position to upper case position through the medium of the lever 24 and said spring, without said spring yielding at any time to permit separation of the finger 29 and its associated pin 14, until stops 50 21 engage stops 22. Continued downward pressure on the key on lever 24 will then cause a slight stretching of the spring and a slight separation of finger 29 from pin 14 until this slight excess movement of the lever 55 24 is arrested by a laterally extending stop lug 32 on the lower end of a stop bar 33 secured by a screw 34 to the key lever guide comb 35 which is mounted on the main frame of the machine. The forward arm of lever 60 24 is arranged to engage said stop lug when 65

depressed a slight distance (approximately $\frac{3}{16}$ inch) after stops 21 and 22 come into engagement to prevent undue movement of the lever but permit sufficient excess motion thereof to allow engagement of the lock nose 70 38 under lock plate 39 with spring 30 stretched slightly more than normally and finger 29 free of pin 14 to insure a secure locking of the parts in upper case position, as hereinafter described, and with lever 24 75 spaced slightly above stop 32. A similar stop device (not shown) is provided for the temporary shift lever 23 to prevent excessive springing of said lever. The shift lever 24 is shown locked with its key-carrying end in depressed position in Fig. 1. This shift lock device comprises the shift-lock key 36 mounted on the upper end of a key stem 37 which is provided at its lower end with the forwardly extending locking lug or nose 38 80 adapted to be rocked under the lower edge of the downwardly and rearwardly inclined lock plate 39 formed on a bracket 40 secured to the main frame of the machine, as above described, after the platen reaches upper 85 case position. The key stem 37 is formed with a forwardly extending arm 41 pivotally held to the lever 24 at 42, and said stem is normally held in upright position by a light, coil return-sprig 43 connected at its 90 upper end to the lever 24 and at its lower end to said key stem, a stop lug 44 on the arm 41 normally abutting against the rear edge of the shift key 28 as shown in Fig. 3. The lock may be released by pressing down 95 on key 28, whereupon spring 43 will release the latch.

A carrying case is provided for the machine comprising a base section 45 and a cover section 46, said case being provided with a suitable handle 47 and the cover section of the case being hinged to the base section by suitable hinge means 48. A suitable lock, not shown, is provided at the forward end of the case for locking the 100 cover in closed position. When it is desired to enclose the machine within the case, the machine is placed in an upright position in the base member 45 and the carriage is positioned substantially midway the length of its travel as is usual in encased portable typewriting machines. In order to keep the dimensions of the case within the lowest possible limit the depth of the case is made such that the cover member 46 can only be 105 fully closed when the platen carriage is in lower case position. It frequently happens, however, that operators of portable typewriting machines will force down the case cover while the platen carriage is locked 110 in upper case position, thereby causing injury to the case shift mechanism. With the case shifting and locking mechanisms constructed as above described, the cover member 115 may be fully closed without releasing the 120 125 130

shift lock without causing any damage to the shifting mechanism, the spring 30 yielding under the abnormal pressure applied to the shift frame in closing the cover to permit the platen carriage to move down to lower case position, as shown in Fig. 2. The cover member of the enclosing casing illustrated in the drawings is provided with one or more brackets 49 of inverted U-shape, the depending arms of which are provided with rubber cushions or bumpers 50 adapted to engage the platen roller 3, when the cover is swung downwardly over the machine with the platen carriage locked in upper case position, to force the platen carriage and its shiftable support to normal lower case position. The cushions 50 and the brackets 49 also serve to hold the platen carriage against case shift movement when the cover is closed, whether the shift lock is in locking position or in release position.

Owing to the arrangement of the parts of the yieldable connection between the shift lever 24 and the shiftable carriage support, and to the fact that stops 19 and 20 are arranged to engage each other before the upper edge of the forward arm of lever 24 reaches the upper end of its guide slot in the comb 35, the spring 30 will only exert a lifting action on the shift frame during downward movement of the key 28 or key 36 notwithstanding the fact that it is normally under tension. Owing to the relative arrangement of the spring 30, the rear arm of lever 24 and the pivot 25, the line of pull on said spring, when either of the keys on lever 24 is depressed, is at all times substantially axially of said spring and parallel with the line of movement of the shift frame.

What I claim is:

1. In a typewriting machine, the combination of a shiftable platen support, a shift key lever, means pivotally supporting said lever intermediate its ends, an abutment shifting with said support engaging the rear end of said lever in such manner as to rock the key-carrying end of the lever downward when the support moves to upper case position and move away from said lever when the support is forced to normal position with the key carrying end of the lever held depressed, a shift lock device for locking the key lever with its key-carrying end depressed, and yieldable means connecting said lever and support of sufficient strength to maintain said lever and abutment in engagement during movements of the platen support from lower to upper case position but adapted, under excessive thrust transmitted to the support when in upper case position in a direction tending to restore said support to normal case position, to yield sufficiently to permit movement of the support

to lower case position while the key lever 65 remains locked.

2. The combination with a typewriting machine having a shiftable platen carriage, of an enclosing case therefor having a cover closable only when the carriage is in lower case position, a shift key lever, a shiftable support for the carriage, a spring connecting said lever with said support for moving the carriage to upper case position when the key carrying end of said lever is depressed, and a shift lock device for locking the key carrying end of said lever depressed, said spring being adapted to yield sufficiently to permit forcing of the platen carriage to lower case position through the medium 80 of said cover.

3. The combination with a typewriting machine having a shiftable platen carriage, of an enclosing case therefor having a cover closable only when the carriage is in lower case position, a shift key lever, a shiftable support for the carriage, a spring connecting said lever with said support for moving the carriage to upper case position when the key carrying end of said lever is depressed, 90 a shift lock device for locking the key carrying end of said lever depressed, and means for normally maintaining said spring under tension, said spring being constructed and arranged to yield sufficiently to permit forcing of the platen carriage to lower case position through the medium of said cover while said lever is locked with its key depressed.

4. The combination with a typewriting machine having a shiftable platen carriage, of an enclosing case therefor having a cover closable only when the carriage is in lower case position, a shift key lever, a shiftable support for the carriage, stops for arresting 100 the support in upper case position, a coiled spring connecting said lever with said support for moving the carriage to upper case position when the key carrying end of said lever is depressed, a latch on said lever for 105 locking the key carrying end of said lever depressed, a stationary abutment adapted to be engaged by said latch upon additional depression of the key-carrying end of the lever after engagement of said stops, and means for normally maintaining said spring under tension sufficient to move the shiftable parts without additional stretching of the spring until said stops engage, said spring being yieldable under key pressure after 110 engagement of the stops to permit locking of the lever and also being constructed and arranged to yield sufficiently to permit forcing of the platen carriage to lower case position by the cover while the lever is locked. 115

5. In a typewriting machine, a shiftable platen support, a key lever for shifting said support pivoted intermediate its ends, a

- 4
- coiled pull-spring connecting said lever back of its pivot with said support for moving said support from lower to upper case position when the key on said lever is depressed, means moving with the support for normally maintaining said spring under sufficient tension to move the support to upper case position without yielding and normally preventing said spring from exerting an effective pull on the support, and a shift lock device for locking said lever with its key depressed.
6. In a typewriting machine, an upwardly shiftable platen carriage support, a shift key lever pivoted intermediate its ends, an abutment shifting with said support and engaging under the rear end of said lever, a coiled spring connected at its upper end with said lever and at its lower end with said support and forming the sole support lifting connection between said lever and support, and a shift lock for locking said key lever with its key depressed, said spring being under sufficient tension to hold said lever against said abutment during upper case-shift movements of the carriage support.
7. In a typewriting machine, an upwardly shiftable platen carriage support, a shift key lever pivoted intermediate its ends, an abutment shifting with said support and engaging under the rear end of said lever, a coiled spring connected at its upper end with said lever and at its lower end with said support and forming the sole support lifting connection between said lever and support, a latch carried by the forward end of the key lever for locking said key lever with its key depressed, a fixed abutment adapted to be engaged by said latch after movement of the key lever in excess of that required to move the support to upper case position, said spring being under sufficient tension to hold said lever against said abutment during upper case shift movements of the carriage support but adapted to yield under excessive strain after the support reaches upper case position, means for arresting the carriage support in upper case position, and means for arresting depression of the key-carrying end of the key lever when the same is depressed beyond the point necessary to permit engagement and release of the latch.
8. In a typewriting machine, a shiftable platen support, a pair of shift key levers pivoted intermediate their ends, means positively connecting one lever adjacent its rear end with the support, a coiled support shifting spring connecting the other lever adjacent its rear end with the support to move the support to upper case position when the key on said lever is depressed, means shifting with the support normally engaged by the last-mentioned lever to main-
- tain said spring under constant tension, lower case stop means for the support, means for arresting the support in upper case position, means for preventing undue depression of the key carrying end of the lever with which said spring is connected, and a shift lock device for locking the latter lever with its key-carrying end depressed.
9. In a typewriting machine, a shiftable platen carriage support, a shift-key lever fulcrumed on a stationary part of the machine, a helical pull spring directly connected at opposite ends thereof with said support and key lever to form a draft connection therebetween for shifting the support to upper case position when the key-carrying end of the lever is depressed, said spring being arranged with its axial line substantially parallel with the direction of movement of the support and the line of pull of the key lever on the spring, and means for locking the shift-key lever with its key-carrying end depressed.
10. In a typewriting machine, a platen carriage, a support for the carriage shiftable diagonally upward and rearward, means for guiding the support, upper and lower case stop devices for limiting shifting movements of the support, a pair of upwardly arched shift key levers, means pivotally supporting said levers substantially at the top of the arch to rock up and down in planes extending fore-and-aft of the machine, means positively connecting the support with the rear end of one lever, a helical support lifting spring connected with the rear arm of the other lever at its upper end and connected at its lower end with said support, said spring extending substantially parallel with the direction of shifting movement of the support, means shiftable with the support engaging under the rear end of the latter lever and maintaining said spring under tension, and a shift lock device for locking the latter lever with its key carrying end depressed.
11. In a typewriting machine, the combination of a main frame, a platen carriage, an upwardly shiftable support for the carriage, means for guiding said support, a transverse rock shaft journaled in said frame, a pair of forwardly extending rock arms on said shaft at opposite sides of the machine, a pair of transverse pins connecting the support with the forward ends of the rock arms, a temporary shift key lever fulcrumed on the main frame at one side of the machine intermediate its ends and provided with superposed fingers at its rear end between which one of said pins extends, a shift and lock key lever fulcrumed on the main frame intermediate its ends at the opposite side of the machine and provided at its rear end with a single finger engaging over the other one of said pins, a

heavy coiled spring connected at its upper end to the shift and lock lever adjacent the rear end of said lever and connected at its lower end with the support, said spring

normally holding said single finger on the shift and lock lever in engagement with the adjacent pin with the spring under ten-

sion, and cooperating means on the shift and lock lever and the main frame for locking said lever with its forward end depressed. 10

In testimony whereof I hereunto affix my signature.

HENRY ALLEN AVERY.
